UNITED STATES PATENT OFFICE.

HARRY HOFFMAN AND LOUIS HOFFMAN, OF PHILADELPHIA, PENNSYLVANIA.

DESIGN FOR A SEEPAGE-INTERCEPTING ATTACHMENT FOR DASHBOARDS.

55,172.

Specification for Design.

Patented May 18, 1920.

Application filed October 16, 1919. Serial No. 331,190. Term of patent 14 years.

To all whom it may concern:

Be it known that we, HARRY HOFFMAN and LOUIS HOFFMAN, residing in Philadelphia, in the county of Philadelphia and State of Pennsylvania, have invented a new, original, and ornamental Design for Seepage - Intercepting Attachment for Dashboards, of which the following is a specification, reference being had to the accompanying drawing, forming a part thereof.

Figure 1 is a perspective view looking

from one side of the seepage intercepting attachment for a dashboard.

Fig. 2 is a perspective view looking from the other side of the seepage intercepting attachment for a dashboard.

We claim:

The ornamental design for a seepage intercepting attachment for dashboards, as shown.

HARRY HOFFMAN.
LOUIS HOFFMAN.
